UNITED STATES PATENT OFFICE.

WILLIAM C. WETMORE, OF BUFFALO, NEW YORK.

TRUSS-PAD.

SPECIFICATION forming part of Letters Patent No. 718,408, dated January 13, 1903.

Application filed December 7, 1901. Serial No. 85,090. (No model.)

To all whom it may concern:

Be it known that I, WILLIAM C. WETMORE, a citizen of the United States, residing at Buffalo, in the county of Erie and State of New York, have invented certain new and useful Improvements in Truss-Pads; and I do hereby declare the following, when taken in connection with the accompanying drawings, to be a full, clear, and exact description of the invention, such as will enable others skilled in the art to which it appertains to make and use the same, reference being had to the accompanying drawings, and to the letters of reference marked thereon, which are to be considered as forming a part of this specification.

My invention provides for the improvement of that class of truss-pads which are inflated with air or water; and it has for its object the production of a pad which is cool and light and which will effectively retain the severest hernia with comfort.

Another object is to provide a truss-pad which will hold all forms of hernia, forming itself to the exact shape of the body and presenting an even rear face without projecting parts, which invariably damage the clothing of the wearer and are also entangled therewith, causing the pad to be displaced.

Other objects are to provide an inflatable pad in which the valve-stem is confined in a pocket provided therefor and which can be made to project from said pocket through the rear wall of the pad for convenience in inflating the same and to provide a protuberance or projection on the face of the pad which is designed to enter the cavity or depression on the person which has been found to exist in some cases.

The invention consists in the new and improved arrangement and combination of parts and in the particular construction thereof, as will be hereinafter pointed out in the appended claims.

Referring to the drawings, Figure 1 is a face view of the truss-pad. Fig. 2 is a rear view of the same, the plate or cover being removed. Fig. 3 is a section taken on a plane indicated by line 3 3, Fig. 1. Fig. 4 is a section taken on a plane indicated by line 4 4, Fig. 3.

Like letters of reference refer to like parts in the several figures.

The letter A designates the forming plate or frame, which is shaped into the form it is desired that the pad should be made, and arranged therein is an elongated opening a.

B designates the elastic or inflatable bulb, which may be inflated with water, air, or any other suitable agency. It is formed to substantially the shape of the forming plate or frame A and has a cavity or pocket b on its flat side and a protuberance b' on its curved or convex side. At the point where the protuberance is formed from the inflatable bulb B it is provided with a contracted neck b², in which the connecting-passage b³ is formed, which latter connects the hollow protuberance with said bulb. This passage in practice is made very small, and therefore permits the protuberance to be greatly distended without proportionately increasing the size of the neck. A valve-stem C is formed on the bulb at one end of the cavity or pocket b and normally assumes a position at an angle 75 to the said flat side thereof, as shown in dotted lines, Fig. 3.

Interposed between the bulb B and the forming plate or frame is an interlining D of leather or other suitable material to prevent injury to the bulb by constant pressure and rubbing on the plate A and also to prevent the screws which enter the forming-plate from coming in contact with the said bulb. This interlining is of substantially the same form as the flat side of the bulb which it protects, and it has an aperture E formed therein, through which the valve-stem C projects.

F designates a covering or inclosure made of non-elastic material or of material having less elasticity than the inflatable bulb confined therein, but which by preference is made of soft leather cut to the desired shape and sewed or otherwise arranged to completely inclose the bulb and forming-plate A except at two points, where it is provided with apertures f f', respectively. The aperture f is preferably of circular form, through which the protuberance b' on the bulb may project, while the aperture f' is elongated and of corresponding shape and size to the aperture a in the forming-plate, with which it coincides.

A plate G is secured to the flat side of the pad, serving as a cover for the cavity or pocket in which the valve-stem is confined and also as a means to which the belt-straps or spring-
5 bands usually employed to hold truss-pads in place may be attached by means of screws or any other suitable arrangement.

As shown in Figs. 2 and 4, the valve-stem is held in the cavity or pocket by placing the
10 outer end of the same underneath the forming plate or frame A, and in order to inflate the bulb it is simply necessary to remove the plate G and release the outer end of the valve-stem, when it will assume a position at an
15 angle to the flat side of the bulb, as shown in Fig. 3, in which position it projects through the elongated apertures in the plate A and inclosure F, permitting the bulb to be inflated with ease and allowing also of the use of a
20 valve within the stem.

In such cases where the protuberance on the pad is desirable the pad is applied to the person before being inflated and the protuberance in its collapsed condition is placed
25 in the cavity on the person. The bulb is then inflated, which causes the protuberance to distend and fill the cavity on the person, thus properly holding the rupture and eliminating all pain. The contracted neck b² permits the protuberance to fill the cavity on a person without crowding the flesh at the entrance thereof, and at the same time permits the pad to act efficiently against the parts surrounding the cavity.
30

35 It is evident that without departing from the scope of my invention the elastic bulb may be formed without the protuberance, as it may be reduced in thickness at the point it is desired the protuberance should be located, and when being inflated that portion reduced in thickness will be forced through the aperture in the inclosure F, thus forming the protuberance.

Having thus described my invention, what
45 I claim is—

1. In a truss-pad, an inflatable bulb having a protuberance projecting therefrom and communicating therewith by an intervening contracted passage, substantially as set forth.
50 2. A truss-pad consisting of an inflatable bulb having an inflatable protuberance, and

a covering for said bulb, said covering being non-elastic or of less elasticity than said bulb and having an aperture through which said protuberance projects, substantially as set forth.

3. A truss-pad consisting of an inflatable bulb having an inflatable communicating protuberance and a non-elastic covering having an aperture through which said protuberance projects, substantially as set forth.

4. A truss-pad consisting of an inflatable bulb having a valve-stem and a cavity or pocket in which said valve-stem is confined, a plate or frame having an aperture through which said valve-stem may project when inflating the bulb, said plate or frame serving to hold the stem in the said cavity, and a second plate serving as a cover to close the said aperture, substantially as set forth.

5. A truss-pad consisting of an inflatable bulb having a valve-stem and a cavity or pocket in which said valve-stem is confined, a plate or frame having an elongated aperture arranged in line with the valve-stem and underneath which the outer end of said valve-stem is held, an inclosure surrounding the inflatable bulb and the said plate, and having an aperture coinciding with the aperture in the latter, and a plate serving as a cover and also as means to secure belt-straps thereto, substantially as set forth.

6. A truss-pad consisting of an inflatable bulb having a valve-stem and a cavity or pocket in which said valve-stem is confined, a plate or frame having an elongated aperture which is arranged in line with the valve-stem and underneath which the outer end of said valve-stem is held, an interlining between the bulb and the said plate, an inclosure surrounding the inflatable bulb and the said plate, and having an aperture coinciding with the aperture in the latter, and a plate serving as a cover and also as means to secure belt-straps thereto, substantially as set forth.

In testimony whereof I have affixed my signature in the presence of two subscribing witnesses.

WILLIAM C. WETMORE.
